UNITED STATES PATENT OFFICE.

JOSEPH DI DARIO, OF ATTLEBORO, MASSACHUSETTS.

HEATER FOR ROTARY BURNISHING IRONS.

Application filed November 2, 1922. Serial No. 598,635.

To all whom it may concern:

Be it known that I, JOSEPH DI DARIO, a citizen of the United States, residing at Attleboro, in the county of Bristol and State 5 of Massachusetts, have invented certain new and useful Improvements in Heaters for Rotary Burnishing Irons; and I do declare the following to be a full, clear, and exact description of the invention, such as will enable others skilled in the art to which it 10 appertains to make and use the same.

My invention has for its object to provide an extremely simple and inexpensive, yet an efficient and desirable heating attachment 15 for shoe repairing and sole-burnishing machines having a rotary burnishing iron, friction alone being relied upon to heat the iron, whereby the expense and inconvenience of gas heaters, is obviated.

20 In carrying out the above end, a pivoted arm is provided for contact with the burnishing iron and a further object of the invention is to provide a latch which is actuated by a spring to normally hold the arm in 25 contact with the burnishing iron, said latch however being also operable to retain the arm in an inoperative position, when it is moved by hand to such a position.

The pivoted arm is provided with a friction 30 shoe for contact with the burnishing iron, in the preferred form of construction, and a further aim of the invention is to provide novel means whereby this shoe may be detachably secured to the arm, so that it 35 may be renewed whenever desired.

With the foregoing in view, the invention, resides in the novel subject matter herein-after described and claimed, the description 40 being supplemented by the accompanying drawing.

Figure 1 is a perspective view of a portion of a sole finishing machine, showing the application of my invention for heating the edge setter, which is merely a rotary burnishing iron for shaping and burnishing the edge of the shoe sole.

Fig. 2 is a side elevation of the invention showing associated parts of the burnishing machine in section.

45 In the drawing above briefly described, the numeral 1 designates the arbor of a sole finishing or burnishing machine, this arbor being rotatable in bearings at the upper ends of vertical standards or frames, one of these 50 bearings being indicated at 2, while its carrying standard or frame is designated by

the numeral 3. A tie rod 4 passes through the standard or frame 3 for tying it to the next adjacent standard or frame in the usual manner. I utilize this tie rod for the 60 purpose of supporting my invention in operative relation with the edge setter or other rotary burnishing iron 5 on the arbor 1.

The numeral 6 designates an upright post which, in the form of construction herein 65 disclosed, is provided with a laterally extending foot 7 having a transverse groove 8 to receive the upper portion of the rod 4. A clamping member 9 is provided at the lower side of the foot 7 and is formed with 70 a groove 10 to receive the lower portion of the rod 4, clamping bolts 11 being passed through the foot 7 and the member 9 for clamping them tightly around the rod 4, to hold the post 6 in upright position. Pivot- 75 ed between its ends to the upper end of the post 6 as indicated at 12, is a horizontal vertically swinging arm 13, the upper end of said post being preferably bifurcated as indicated at 14 for the reception of said arm. 80 In the form of construction herein disclosed, the front end of the arm 13 is provided with a friction shoe 15 formed of rubber or any other suitable material and adapted to contact with the rotary burnishing iron 5. 85 While any suitable means may be employed for detachably securing the shoe 15 upon the arm 13, I prefer to provide a pair of clamping plates 16 secured against opposite sides of the arm by screws or the like 17, 90 said plates extending below said arm to clamp against opposite sides of a rib 18 with which the shoe 15 may be provided. If desired, the rib and the coacting portions of the plates 16 may be of dove-tail formation 95 as shown in Fig. 1.

I have shown a coil spring 19 connecting the front end portion of the arm 13 with the post 6 and exerting a downward pull on said arm to assist in properly holding the 100 shoe 15 in contact with the burnishing iron 5. A spring operated latch 20 also assists in this operation, and will be fully described below.

The latch 20 is in the form of a substantially straight arm having its lower end pivoted at 21 to the post 6 at a point spaced below the arm 13, said latch converging rearwardly with the rear end of said arm 13 and being held in contact with the beveled 110 rear extremity of this arm, by a coiled spring 22. By pivoting the latch 20 in the

manner set forth, spring 22 pulls it upwardly against the rear end of the arm 13, thereby tending to swing the front end of this arm downwardly and increasing the friction existing between the shoe 15 and the burnishing iron 5. It will be obvious that if the spring 22 is of sufficient strength, the spring 19 might be dispensed with.

In addition to performing the function above set forth, the latch 20 is operative to hold the arm 13 in an inoperative position, when moved by hand to such a position. For this purpose, the latch 20 is provided with a notch 23 to receive the beveled rear extremity of the arm, as shown in dotted lines in Fig. 2.

By employing the construction shown, a heater is provided which is of simple and inexpensive construction, yet it will be highly efficient and in every way desirable. Whenever the use of the device is not necessary, it may be held in an inoperative position by the latch 20 and it will be obvious that the shoe 15 may be renewed whenever desired.

As excellent results may be obtained from the details disclosed, they are preferably followed, but within the scope of the invention as claimed, numerous minor changes may be made.

I claim:—

1. A heater for a rotary sole-burnisher comprising a post, means for securing it to a frame of a sole-burnishing machine, a vertically swinging arm pivoted to said post and adapted to contact with the burnishing iron, a spring acting on said arm for holding

the same in tight contact with the iron, and a latch associated with said arm and post for holding the arm in inoperative position when desired. 40

2. A heater for a rotary sole-burnishing iron comprising a pivoted arm and means for mounting it on the frame of a sole-burnishing machine, and a spring-actuated latch normally bearing against said arm to force it against the burnishing iron, said latch being operable to hold the arm in an inoperative position when moved to such a position. 50

3. A heater for a rotary sole-burnishing iron comprising a support and means for mounting it on the frame of a sole burnishing machine, an arm pivoted between its ends to said support and having one end adapted to contact with the iron, a latch pivoted to said support below said arm and converging with the other end of the latter, and a spring tending to move said latch constantly upward whereby to force against said arm and hold it in operative position, said latch and arm being cooperable to hold the latter in inoperative position when moved to such a position. 55

4. A heater for a rotary burnishing iron comprising a shoe for contact with the iron, a carrying member for said shoe, and a pair of clamping plates secured against opposite sides of said shoe and arm for holding the one on the other. 60 65

In testimony whereof I have hereunto affixed my signature.

JOSEPH DI DARIO.
